United States Patent Office.

NICHOLAS S. VEDDER, OF TROY, AND TOBIAS S. HEISTER, OF LANSINGBURG, NEW YORK, ASSIGNORS TO NICHOLAS S. VEDDER.

Design No. 3,866, dated February 22, 1870.

DESIGN FOR A STOVE-PLATE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented and produced a new and original Design for Plates of a Cooking-Stove, of which the following is a specification, reference being had to the accompanying photographic illustration.

The design for the large oven-door A consists of the compound center ornament *a b c d* on the plane surface *e*, surrounded by the ornamental border *f g*, all shaped and disposed so as to appear as represented in said photograph.

The design for the door or panel H at the end of the fire-box consists of the compound ornament *i* on the plane surface *j*, surrounded by the border-molding *k*, as shown in said illustration.

The design for the lower front door L consists of the border-molding *m* around the oblong openings *n*, and for the upper front doors O of the border-molding *p* around the smooth surface *q*, all shaped and arranged as particularly shown in the said photographic representation.

And the design for the foot R is as represented in the said photographic illustration.

What we claim as our joint invention and production, and desire to secure by Letters Patent, is—

The design for the plates or parts A, H, L, O, and R of a cooking-stove, as herein described and shown.

NICHOLAS S. VEDDER.
TOBIAS S. HEISTER.
